DESIGN FOR A HYGROMETER OR THE LIKE

John Leonard Schwartz, Philadelphia, Pa.

Application March 6, 1946, Serial No. 127,141

Term of patent 3½ years

(Cl. D52—7)

To all whom it may concern:

Be it known that I, John Leonard Schwartz, residing in Philadelphia, county of Philadelphia, State of Pennsylvania, have invented a new, original, and ornamental Design for a Hygrometer or the like, of which the following is a specification, reference being had to the accompanying drawings, forming part thereof.

Fig. 1 represents a front elevational view of a hygrometer or the like showing my new design.

Fig. 2 represents a side elevation thereof.

The essential features of my design reside in the portions shown in full lines.

I claim:

The ornamental design for a hygrometer or the like, as shown and described.

JOHN LEONARD SCHWARTZ.
